Primary Examiner — Jeffrey D Asch*Assistant Examiner* — Sanjeev Paul(74) *Attorney, Agent, or Firm* — Birch, Stewart, Kolasch & Birch, LLP**CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image; and

FIG. 6 is a front perspective view thereof showing an example of the usage of the subject design; and,

FIG. 7 is a rear perspective view thereof showing an example of the usage of the subject design.

The broken lines shown in the figures that are immediately adjacent to the shaded areas and define unshaded regions represent the bounds of the claim, while all other broken lines, including those within the broken line boundaries and those showing displayed information are directed to non-claimed environment; the broken lines form no part of the claimed design.
